Des. 237,840
Patented Nov. 25, 1975

237,840

HAIR DRYER

Paul O. Rawson, 50 Sherwood Drive,
Easton, Conn. 06612

Filed May 17, 1974, Ser. No. 470,887

Term of patent 14 years

Int. Cl. D28—03

U.S. Cl. D86—10 F

FIG. 1 is a perspective view of a hair dryer as viewed from the front;

FIG. 2 is a perspective view thereof as viewed from the rear and the opposite side of the view of FIG. 1 showing my new design;

FIG. 3 is a side elevational view thereof;

FIG. 4 is a front elevational view thereof;

FIG. 5 is a rear elevational view thereof; and

FIG. 6 is a bottom plan view thereof.

I claim:

The ornamental design for a hair dryer, as shown and described.
